Inventor
Sydney Paul;

By Robert W. Kaudle,

Attorney

UNITED STATES PATENT OFFICE.

SYDNEY PAUL, OF LIMA, OHIO, ASSIGNOR TO SUPERIOR MOTOR COACH BODY CO., OF LIMA, OHIO, A CORPORATION OF OHIO.

MOTOR-COACH CHAIR.

Application filed January 31, 1925. Serial No. 5,932.

The object of my present invention, broadly speaking, is to provide a chair especially intended for vehicles, the same being strong and durable in construction, neat and attractive in appearance, comfortable for the person seated thereon, and which can be manufactured, sold, and installed at a comparative low price.

More specifically stated, my object is to provide a chair adapted for providing a maximum of seating capacity in commercial vehicles, such as motor coaches or busses, having means for obtaining the maximum of comfort for the user thereof, occupying a minimum of space, providing a maximum of resiliency, and having means for the absorption of sudden starts incident to such vehicles, and having means whereby the chair may be turned forward for the purpose of cleaning thereunder.

Other objects and particular advantages of the invention will suggest themselves in the course of the following description, and that which is new will be correlated in the appended claim.

The means for carrying out the objects and the principles of my invention in a practical manner is shown most clearly in the accompanying two sheets of drawings, in which—

Figure 1 is a perspective view of my chair, as it would appear in actual use. Figure 2 is a plan view of the lower portion of the chair, the cushion being removed, and showing the upwardly extending portions in section. Figure 3 is a section as taken on the line 3—3 of Fig. 1. Figure 4 is a cross section of the base frame. Figure 5 is a skeletonized view showing the bare frame-work of the chair. Figure 6 is a cross section of the lower portion of the chair. Figure 7 is a front elevation of the lower portion. And Figure 8 is a vertical section of one of the shock absorbers.

Similar indices denote like parts throughout the several views.

In order that the construction, the operation, and the several advantages of my invention may be more fully understood and appreciated, I will now take up a detailed description of same, in which I will set forth the same as comprehensively as I may.

The main frame portion of my chair comprises a single piece of laminated wood stock, bent to substantially the shape shown

in Fig. 5, to form the front feet 1 and 2; the front legs 3 and 4; the arms 5 and 6; the sides 7 and 8 of the back; and the central portion 9.

Formed of the same character of material as are said parts, are the rear legs 10 and 11, each having a foot, 12 and 13 respectively.

The upper ends of the legs 10 and 11 are formed tapering, as shown at 14 in Fig. 5, where they are rigidly secured to the juncture between the members 6 and 8, and in like manner the upper end of the leg 10 is secured to the juncture of the members 5 and 7.

Numerical 15 denotes the base frame, which is substantially square with rounded corners, and it is formed endless, of a single length of laminated wood stock, as is indicated in the drawings.

Each of the legs 3, 4, 10 and 11, are secured to the outside face of the respective corners of said frame, whereby the frame is supported in the manner shown.

Secured on the outer faces of the sides of the frame 15 are the reinforcing plates 28 and 29, the same extend from the respective legs 3 and 4, with their rear ends tapering to a feather near the rear corners of the frame, as is indicated in Fig. 2.

The said parts 3, 4, 5, 6, 7, 8, 9, 10, 11, 28 and 29 are upholstered in any material desired, such as leather, as indicated by the respective numerals 30, 31, 32, 33, 34, 35, 36, 37, 38, 39, 40 and 41.

The upholstering 42 extends between the members 7, 8, 9 and 15 and forms the real back of the chair. It is to be understood that the upholstering 42 is supported by the usual backing, not shown.

Secured to the inner face of the base frame 15, located at each of the corners thereof, are the brackets 16, 17, 18 and 19, each of which has an inturned horizontal portion on which are secured the lower ends of the respective helical springs 20, 21, 22 and 23.

The upper portion of each two of said springs are connected by a wire or rod, as designated by the numerals 24, 25, 26 and 27. Numerical 43 denotes a box-like upholstered spring-cushion, which corresponds in shape with the shape of the base frame 15, and it is adapted to be placed therein and rest on the upper ends of the springs 20, 21, 22 and 23.

22 and 23, whereby the cushion is resiliently mounted.

The chair above described is adapted to be connected with a floor A by two shock absorbing devices, with which the legs 1 and 2 are connected as shown, in Figs. 1, 6 and 7.

Each of said devices comprises a cylinder 44, which is disposed at an angle extending rearward and upward from the floor. Each 10 of said cylinders has a foot 44 to rest flat on the floor A, with apertures therein to receive the bolts 46, whereby the cylinder is rigidly secured to the floor A as shown.

Each of said cylinders has an aperture 15 through the center of its upper end, from around which the tubular guide 47 extends downward some distance into the cylinder. Slidable in the tubular guide 47 is the rod 48, which carries on its lower end the head 20 49.

Numeral 50 denotes a coil spring which surrounds the guide 47, with its upper end contacting with the top of the cylinder, and its lower end contacting with the top of the 25 head 49. The under face of the head 59 is formed concave in order to fit over the top of the foot 1, or 2.

Through each side of the lower end of the cylinder there is formed an opening 51 to receive the foot 1, or 2, freely therein.

The rod 48 projects at all times above the upper end of the cylinder, and through the projecting portion an aperture 52 is formed to receive the detachable hook 53, whereby 35 the head 49 may be lifted up against the resiliency of the spring 50.

From the above it will be apparent that I provide a chair which is very light in weight, yet having a maximum of strength, 40 in which a maximum of resiliency is provided for a person located on the cushion, by reason of the springs 20, 21, 22 and 23, plus the usual springs inside the cushion.

Now assuming that the chair is located on

the floor of a vehicle, in the manner shown, 45 it is apparent that a sudden jerk forward will permit the chair to top slightly rearward, against the resiliency of the springs 50, thereby reducing the effect of the jerk with relation to the user of the chair.

This means of attaching the chair to the floor also permits the chair to be turned forward without resistance, but it prevents it from being moved by the passenger using it, but means are provided for its removal 55 by an authorized person having the key 53 with which to pull the heads 49 upward out of contact with the feet.

It is to be understood that various changes may be made in the several details herein set 60 forth without departing from the spirit of the invention and without sacrificing any of the advantages thereof which are new and useful and which involve invention.

Having now fully shown and described 65 the invention, what I claim and desire to secure by Letters Patent of the United States, is—

A chair comprising a curved back-frame, curved arms, front legs, and front feet 70 curved inwardly at right-angles to the legs, all of said parts being formed of a single length of laminated wood; rear legs extending downward from the junctures of said back-frame and arms, feet curved inwardly 75 at right-angles from said rear legs, each of said rear legs and its foot being formed of a single length of laminated wood; an endless base frame formed of a single piece of laminated wood and attached to each of said 80 legs and extending therebetween, a cushion adapted to fit in said base frame, and means for resiliently supporting the cushion in the base-frame.

In testimony whereof I have hereunto subscribed my name.

SYDNEY PAUL.
